CONVERSION OF HYDROCARBON OILS

William J. Sweeney, Summit, N. J., assignor to
Standard Oil Development Company, a corpora-
tion of Delaware

Application November 3, 1944, Serial No. 561,673

3 Claims. (Cl. 196—52)

1

This invention relates to the conversion of hydrocarbon oils and pertains more particularly to the production of aviation gasoline from higher boiling oil.

It is now commonly known that gasolines produced by conventional catalytic cracking processes contain relatively high concentrations of olefinic and other unsaturated constituents which are undesirable in aviation gasoline. It is likewise known that the olefinic constituents are more highly concentrated in the lower boiling fraction of the gasoline produced from the catalytic cracking operation.

Various methods have heretofore been proposed for removing the olefinic constituents from the gasoline obtained from catalytic cracking operations. These methods may include, for example, acid treatment, solvent extraction, polymerization, alkylation, re-cracking and hydrogenation.

It has likewise been found that while the higher boiling fraction of catalytic gasoline contains a relatively high concentration of aromatics and a relatively low concentration of olefinic constituents, as compared with the lower boiling fraction, the higher boiling fraction also contains constituents which tend to impair and degrade the quality of aviation gasoline.

In view of this, it has been proposed to subject the heavier fraction of the catalytic naphtha to further catalytic treatment in the presence of the same general type of catalyst employed during the catalytic cracking and under the same general operating conditions. This retreating of the gasoline effects a material improvement in the quality of the gasoline product.

According to one type of procedure heretofore proposed, the naphtha formed from a catalytic cracking operation is segregated into a light naphtha fraction, such as a fraction boiling below 200° F., and a heavier naphtha fraction boiling between 200° F. and the end point of the gasoline. The light naphtha fraction so separated is then hydrogenated to saturate the olefinic constituents and the heavier naphtha is subjected to further cracking treatment, preferably at lower temperatures than are employed in the primary cracking operation. The retreated heavy naphtha and the hydrogenated light naphtha may then be blended into the final gasoline product, together with the addition of an alkylate or other addition agent, for producing the final market aviation gasoline.

One of the principal objects of the present invention is to provide a process of the general type

2

above outlined which will produce an improved yield of higher quality aviation gasoline.

Other more specific and detailed objects of the invention will be apparent hereinafter.

5 In accordance with the broader phases of the present invention, a higher boiling oil, such as a gas oil or reduced crude, is initially subjected to a catalytic cracking operation. The cracked vapors are thereafter fractionated to segregate a light naphtha fraction and a heavier naphtha fraction. The heavier naphtha fraction so separated is then subjected to a re-cracking treatment in the presence of a catalyst and the re-cracked or retreated product is separately fractionated to separate a light naphtha and a heavy naphtha.

10 15 The heavy naphtha so separated is withdrawn as a final product of the process. The light naphtha formed during the retreating operation is then intermixed or combined with the light naphtha formed during the primary cracking process. This combined stream is thereafter subjected to further treatment for removal of the olefinic constituents therefrom and then blended with the retreated heavy naphtha.

20 25 30 According to a further modification of the invention, the light naphtha formed during the initial catalytic cracking process and during the aftertreating of the heavy naphtha fraction obtained therefrom is further separated into a fraction consisting principally of C₅ hydrocarbons and a fraction consisting principally of C₆ hydrocarbons. The C₅ hydrocarbon fraction is thereafter separately treated, as hereinafter described, and the C₆ fraction is subjected to hydrogenation, as previously described.

35 40 45 In accordance with another more specific phase of the present invention, the cracked vapors from the initial and aftertreating operations are fractionated to segregate a light naphtha fraction boiling up to about 150° F. and a second naphtha fraction boiling between about 150° F. and the final end point of the naphtha.

It has been found, for example, that a substantial improvement in the character and yield of the products may be realized by careful selection of the cut point between the light and heavy naphthas formed during the cracking treatment. By cutting the fractions at about 150° F. the hydrocarbons having 7 carbon atoms or more per molecule will appear mainly in the heavy naphtha and therefore be subjected to the aftertreating operations previously described, whereas the light naphtha fraction will consist mainly of hydrocarbons containing 5 or 6 carbon atoms per molecule. It has been found, for example, that

the hydrocarbon fraction consisting principally of hydrocarbons containing 7 carbon atoms per molecule is more advantageously treated by the re-cracking or retreating operation than by the hydrogenation treatment given to the lower boiling fraction.

With the above general nature and objects in view, the invention will be best understood by the more detailed description hereinafter in which reference will be made to the accompanying drawings forming a part of the disclosure and illustrating in a diagrammatic manner an apparatus suitable for carrying the invention into effect. In the drawings

Fig. 1 is a diagrammatic illustration of the catalytic cracking and retreating steps in the process, together with the initial fractionation of the products, and

Fig. 1A is an extension of Fig. 1 illustrating the hydrogenation and alkylation steps, together with a more complete separating and fractionating equipment.

Referring to the drawing, reference character 10 designates a charge line into which a higher boiling oil to be processed is introduced into the equipment. This oil may comprise any higher boiling natural or synthetic petroleum stock which is to be converted into lower boiling motor fuel. For example, the oil may be a clean condensate stock of gas oil boiling range, or it may comprise a crude or reduced crude. The oil passing through line 10 is intermixed with a cracking catalyst which is continuously discharged therein through a vertical conduit 11. This catalyst may be any of the commonly known cracking catalysts, such as silica-alumina, silica-magnesia, alumina-boria, silica-zirconia, or mixtures thereof.

For illustrative purposes, the cracking operation is shown in the form of a fluid catalyst cracking equipment in which the catalyst in finely divided form while in fluid state is caused to circulate continuously through a cracking chamber and a regenerating chamber. In this operation the loss in pressure on the catalyst resulting from the circulation through the chambers is restored by means of a standpipe in which the necessary pressure is generated to effect the circulation.

Furthermore, in this type of operation the oil vapors and regenerating gas are passed upwardly through the cracking and regenerating zones, respectively, at a velocity controlled to maintain a dense, turbulent layer of catalytic material in the bottom portion of the chamber superimposed by a dilute mixture of gases and catalyst in the upper portion.

The oil passing through line 10 may be pre-heated, or the necessary amount of heat for the cracking operation may be obtained from the hot regenerated catalyst being introduced therein through conduit 11. The mixture of hot regenerated catalyst and oil vapors formed in the line 10 continues through line 10 into the bottom section of a cracking chamber 12 through a distributing cone 13. The oil vapors pass upwardly through the cracking chamber 12 at a velocity controlled to maintain a dense, turbulent layer of catalytic material, as indicated on the drawing and as previously described. The vaporous reaction products are removed from the upper portion of the cracking chamber 12 through a cyclone separator 14 which may be mounted in the upper part of the reaction chamber. The cracked vapors withdrawn from the top of the cracking

chamber pass through line 15 to a primary fractionating tower 16 in which constituents boiling above the desired motor fuel fraction are condensed. The fractionating tower may be provided with one or more trap-out trays for segregating the different fractions of said higher boiling constituents.

The initial condensate formed in the bottom section of the primary fractionating tower 16 is withdrawn through line 17. This fraction may contain a small amount of entrained catalyst carried overhead from the reaction chamber 12 through line 15. This fraction may be treated in equipment (not shown) for removing the catalyst therefrom, or the fraction may be recirculated from line 17 through pump 18 and line 19 which merges with the charge line 10. An intermediate gas oil cut may be collected in a trap-out tray 21 of the fractionating tower 16 and may be withdrawn therefrom through line 22.

Vapors remaining uncondensed in the fractionating tower 16 and consisting of normally gaseous constituents together with the desired motor fuel fraction are removed overhead through line 23 to a condenser 24 in which the desired distillate is condensed. The products from the condenser 24 may then pass to a product receiver 25 in which the liquid distillate formed in the condenser 24 may be separated from the normally gaseous constituents. This normally gaseous fraction is removed from the product receiver 25 through line 26. This fraction may consist principally of C₃ and lower boiling hydrocarbons.

The liquid distillate comprising the motor fuel constituents including the C₄ hydrocarbons is withdrawn from the bottom of the product receiver 25 through line 27 and may be passed to an after-fractionator 28. The top temperature of the after-fractionator 28 may be regulated to take overhead through line 29 a vaporous fraction consisting principally of hydrocarbons boiling below about 150° F. and comprising the C₄, C₅ and C₆ hydrocarbons.

Unvaporized distillate is continuously withdrawn from the after-fractionator 28 through line 31. This distillate fraction, which may boil between 150° F. and 450° F., is subjected to further cracking treatment. To this end, the product withdrawn from the receiver 28 through line 31 is passed by means of pump 32 to line 33 into which additional catalyst is discharged through conduit 34. The resulting mixture of heavy naphtha and catalyst is thereafter passed through line 33 into the bottom section of a retreating chamber 35 through a distributing cone 36. The temperature within the retreating chamber 35 may range from 600° F. to 1000° F. The heat necessary to maintain the desired temperature may be supplied by hot regenerated catalyst discharging through line 34, or the distillate fraction may be subjected to suitable pre-heating before or after intermixing with the catalyst. The retreated vapors after passing through the conversion chamber 35 are removed overhead through a cyclone separator 37 and line 38 to a separate fractionating tower 39 in which they are subjected to independent fractionation to remove higher boiling polymers formed during the retreating operation. The higher boiling polymers or other constituents formed during the cracking operation are removed from the fractionating tower 39 through line 41 and may be combined with the cycle oil from the primary fractionating tower 16 and returned to the primary cracking treatment.

The vapors remaining uncondensed in the fractionating tower 39 are removed overhead through line 42 to a separate condenser 43 in which the normally liquid products are condensed. These products then pass to a second product receiver 44 in which normally gaseous material formed during the retreating operation is separated from the liquid distillate formed in the condenser 43. The gaseous fraction separated from the liquid distillate in the receiver 44 is removed overhead through line 45. This product may be combined with the gaseous fraction removed from the product receiver 26 and may be passed to suitable absorption equipment for removal of the desired constituents therefrom. The normally liquid constituents formed in the product receiver 44 are withdrawn through line 46 to a stabilizing tower 47 in which the products are subjected to combined distillation and fractionation to separate the same into a lower boiling and a higher boiling fraction. The top temperature of the stabilizing tower 47 may be maintained at the same temperature as the after-fractionating tower 28 so as to take overhead through line 48 a lower boiling fraction boiling below about 150° F.

The retreated heavy naphtha fraction is withdrawn from the stabilizing tower 47 through line 49 as a final product of the process. The light naphtha fraction recovered from the after-fractionating tower 28 and the light naphtha fraction recovered from the stabilizing tower 47 are thereafter combined and may be passed to a butane tower 51 illustrated in Fig. 1A. Tower 51 is maintained under conditions controlled to remove overhead through line 52 the C₄ hydrocarbons. These products may be passed to an alkylation zone indicated symbolically by the rectangle 53 in which they are subjected to alkylation with or without extraneous isoparaffins and olefins. The debutanized product is withdrawn from the bottom of the butane tower 51 through line 54.

According to one modification of the invention, this product, consisting largely of the C₅ and C₆ hydrocarbons, is passed through line 55 to a hydrogenation unit 56 in which it is subjected to low temperature catalytic hydrogenation for saturating the olefinic constituents contained therein. This hydrogenation may be carried out at temperatures of from 500° F. to 1000° F. and in the presence of various hydrogenating catalysts. The hydrogenated product may then be combined with the retreated heavy naphtha withdrawn from the bottom of the stabilizing tower 47. If desired, the hydrogenated products may be subjected to redistillation and fractionation before being blended with the retreated heavy naphtha.

According to another phase of the present invention, the product withdrawn from the bottom of the butane tower 51 is passed through line 57 to a pentane tower 58 which is controlled to take overhead a fraction consisting principally of C₅ hydrocarbons. The remaining unvaporized fraction is withdrawn from the pentane tower 58 through line 59 and is passed to the hydrogenation unit 56 previously described.

The C₅ fraction removed overhead from the pentane tower 58 through line 61 is then subjected to separate distillation and fractionation in tower 62 to separate a fraction rich in iso constituents and a fraction rich in normal constituents. The fraction consisting principally of normal constituents is removed from the tower 62

through line 63 and is utilized in automotive fuel or otherwise rejected from the process.

The fraction consisting principally of iso constituents is removed overhead from the tower 62 through line 64 and is passed to the alkylation unit 53 in which the isoolefins are alkylated along with the C₄ hydrocarbons and thereby remove the isopentene constituents from this fraction. The products from the alkylation unit may then pass to a suitable distillation and fractionation tower 65 for separation of the desired aviation alkylate.

Unreacted C₄ and C₅ hydrocarbons are removed from the tower 65 through line 66 and may be passed to a butane tower 67 in which the butane is separated from the isopentane. The isopentane is withdrawn from the bottom of the butane tower 67 through line 68 and may be blended with the hydrogenated C₆ hydrocarbons and aftertreated heavy naphtha. The aviation alkylate formed in the process may likewise be combined with the retreated and hydrogenated product. The vapors from the butane tower 67 may be passed into a second fractionating tower 69 for separation of the unreacted isobutane from the normal butane. The normal butane may be withdrawn from the tower 69 through line 71 and rejected from the process, and the isobutane may be condensed and recirculated to the alkylation unit 53.

No attempts will be made to describe in detail the conditions for effecting the alkylation of the C₄ and C₅ hydrocarbons, since these conditions are well known in the art and subsequent equipment necessary for effecting the separation and segregation of the resulting products is likewise too well known to warrant further description.

The initial cracking of the original charging oil may be carried out at any desired temperature, such as from 800° F. to 1000° F. or more, and under a pressure ranging from atmospheric to 100 lbs./sq. in. The weight of oil treated per weight of catalyst in the cracking chamber 12 may be of the order of from 0.5 to 5 parts of oil per hour per part of catalyst by weight.

The amount of catalyst introduced into the oil stream may vary over an extended range, such as from 1 to 50 or more parts of catalyst per part of oil, both in the cracking and in the re-treating operations.

A stream of catalyst is continuously withdrawn from the cracking chamber 12 through a vertical conduit 75 which discharges into a stream of air passing through line 76 and is passed into the bottom portion of a regenerator 77 in which carbonaceous deposits formed during the cracking operation are removed. Likewise, a stream of catalyst is continuously withdrawn from the retreating chamber through a vertical conduit 78 which discharges into the air line 76. Regenerated catalyst is continuously withdrawn from the common regenerator 77 through conduits 11 and 34 for return to the primary and secondary stages, respectively.

The air velocity passing upwardly through the regenerator 77 is preferably controlled, as previously described, to maintain a relatively dense, fluidized, turbulent layer of catalytic material undergoing regeneration within the regenerator 77. Spent regenerating gas is removed from the top of the regenerating chamber 77 through a cyclone separator 79 and line 80. This stream may be passed to further equipment for the removal of the final traces of catalyst. This equip-

ment has been omitted in the interest of simplicity.

Instead of using a common regenerator 77 for effecting regeneration of the catalyst employed both in the retreating and cracking operations, separate regenerators may be provided and in some cases it may be desirable to use a catalyst in the retreating operation of a different composition than that employed in the cracking operation. In this connection, it is particularly advantageous to employ a highly active cracking catalyst for carrying out the retreating. The cracking and retreating equipment illustrated in the drawing is intended to show a conventional fluid catalyst process, as previously mentioned, wherein the finely divided catalyst is continuously circulated in the fluid state through the cracking, retreating and regenerating zones. In order to maintain the desired fluidity, a small amount of aerating or fluidizing gas may be introduced at any point in the system, such as standpipes 11, 14, 15 and 18, wherein catalyst tends to settle into a dense, stationary body.

Having described the preferred embodiment of the invention, it will be understood that it embraces such other variations and modifications as come within the spirit and scope thereof.

What is desired to be protected by Letters Patent is:

1. A process for the production of gasoline suitable for aviation fuel which comprises subjecting a higher boiling oil to cracking under conditions controlled to produce an olefinic gasoline fraction, separating the gasoline fraction so produced into a higher boiling naphtha fraction and a lower boiling naphtha fraction, subjecting said higher boiling naphtha fraction to separate further cracking treatment, separating the re-cracked naphtha into a light naphtha fraction and a heavy naphtha fraction, combining said re-cracked light naphtha fraction with the lower boiling naphtha fraction from the first-mentioned cracking treatment, treating the combined light naphtha fraction to remove olefinic constituents therefrom, and thereafter combining the treated light

naphtha fraction with said re-cracked heavy naphtha fraction.

2. In the process defined by claim 1, the further improvement which comprises cutting the naphthas obtained from both the cracking and re-cracking operations so that the lower boiling naphtha fraction has an end point below about 150° F.

3. A process for the production of gasoline suitable for aviation fuel which comprises subjecting a higher boiling oil to cracking in the presence of an active cracking catalyst under conditions controlled to form an olefinic gasoline fraction, separating from the cracked products a lower boiling naphtha fraction boiling below about 150° F. and a higher boiling naphtha fraction, subjecting said higher boiling naphtha fraction to further cracking treatment in the presence of an active cracking catalyst, separating from the re-cracked products a lower boiling naphtha fraction of substantially the same boiling range as said first-named lower boiling naphtha fraction and a higher boiling naphtha fraction, combining said last-named lower boiling naphtha fraction with said first-named lower boiling naphtha fraction, hydrogenating the combined products to saturate olefinic constituents contained therein, and thereafter combining the hydrogenated lower boiling naphtha fraction with said heavier re-cracked naphtha fraction.
